[57] CLAIM

The ornamental design for a game machine, as shown and described.

DESCRIPTION

FIG. 1 is a perspective view of a game machine; FIG. 2 is a front view of the game machine; FIG. 3 is a rear view of the game machine; FIG. 4 is a left side view of the game machine; FIG. 5 is a right side view of the game machine; FIG. 6 is a top view of the game machine; FIG. 7 is a bottom view of the game machine; FIG. 8 is a view of a section taken along the line 8—8 in FIG. 2; FIG. 9 is a view of a section taken along the line 9—9 in FIG. 2; FIG. 10 is a view of a section taken along the line 10—10 in FIG. 4; FIG. 11 is a perspective view of a second embodiment of the game machine; and, FIG. 12 is a perspective view of a third embodiment of the game machine. The corresponding views of the second (FIG. 11) and the third (FIG. 12) embodiments are similar to that of FIGS. 1—7 of the first embodiment.
